CAN CLOSING MACHINE

Herbert L. Minaker, Syracuse, N. Y., assignor to
 Continental Can Company, Inc., New York,
 N. Y., a corporation of New York

Application August 3, 1940, Serial No. 350,930

7 Claims. (Cl. 226—82)

The present invention relates to new and useful improvements in a can closing machine, and more particularly to improvements in means for eliminating air from the head space of a filled can prior to or at the time of closing the can.

An object of the present invention is to provide a can closing machine with means for passing steam across the head space of the filled can so as to eliminate air therefrom during relative movement between the can and the can end at the seaming station for placing the can and the can end in proper position preparatory to the seaming operation.

A further object of the invention is to provide a can closing machine of the above type wherein the supporting or centering plate is constructed and arranged so as to provide means for directing steam in one direction across the head space of the filled can for effectively driving out the air while the can and the can end are moved relative to one another at the seaming station preparatory to the seaming operation.

A still further object of the invention is to provide a can closing machine of the above type wherein high pressure steam is employed for completely driving out the air from the head space of the filled can and for heating up the head space and the top of the can so as to obtain the desired vacuum within the can when closed.

The above and other objects of the invention will in part be obvious and will in part be hereinafter more fully disclosed.

In the accompanying drawings—

Figure 1 is a top plan view showing the opening beneath the stack holder, the can end support beneath the seaming head, and the means for feeding the can end from the stack holder to the can end support;

Fig. 2 is a fragmentary side sectional view taken along the line 2—2 of Fig. 1, showing the relative positions of the seaming head, the can end and the can body while the steam is directed across the head space of the filled can, and

Fig. 3 is a side sectional view taken substantially along the line 3—3 of Fig. 1, and showing the steam valve control mechanism.

It is to be clearly understood that the essential features of the present invention can be employed with various types of can closing machines. However, for reference purposes, the stack holder and the support for the can end at the seaming station may be substantially of the types shown in the Bratt & Fluck Patent #1,387,098, dated August 9, 1921, or in the Fink Patent #1,653,557, dated December 20, 1927. Similarly, the mecha-

nism for feeding the can bodies and for elevating the can bodies at the seaming station may be of the type shown in the Warne Patent #1,307,888, dated June 24, 1919.

Referring more in detail to the accompanying drawings, the supporting or centering plate 10 is suitably mounted on the frame of the machine and is provided with cover plates 11, 12 which are secured thereto by screws 11a, 12a, or the like. The plate 12 has an opening 13 therethrough and this opening is located directly beneath the holder for the stack of can ends which are to be delivered by gravity to a race or trackway 14. This race or trackway for the can ends C extends from the opening beneath the stack holder to a seat 15 for the can end at the seaming station and beneath the seaming head. Each can end is moved from beneath the stack holder to the seat 15 at the seaming station by an arm 16 which rotates with the shaft 17 vertically carried within the sleeve 17a on the supporting plate 10.

As pointed out in the above-mentioned Bratt & Fluck patent, the rotating arm 16 may be provided with an elevated end 18 which moves within the space 14a between the sides of the race 14 and is adapted to overlie the edge of the can end so as to hold the can end against the face of the arm as it is moved along the trackway toward the seaming station. The trackway is disposed in part concentric with the center of movement of the arm 16 and in part eccentric thereto, so that the can end gradually moves outwardly relative to the arm 16 during movement of the can end toward the seaming station. This shaping of the trackway is such as to finally bring the can end to a position on the seat 15 at the seaming station, at which time the arm 16 can pass the edge of the seated can end. Further rotation of the arm 16 will bring the same into engagement with another can end beneath the stack holder.

The seaming head may, as indicated above, be of the type shown in the Warne Patent #1,307,888, which includes conventional seaming rolls 19, 20, and a chuck 21 with which the seaming rolls cooperate during the seaming of the can end to the can body. There is also provided a stripper pad 22 which is associated with the chuck 21. The can body B may be fed to the can support 23 in any suitable manner, as for instance, by a rotating drum conveyor of the type shown in the above-mentioned Warne patent, and a guide 24 may be provided for properly locating the can body on the support 23. Beneath the seaming head, the supporting plate 10 is pro-

vided with a tapered centering opening 25 which is located below the seat 15 for the can end. The surface of the centering opening 25 is for the purpose of centering the can body and for rounding up the upper end of the can body when it is elevated by upward movement of the support 23 prior to the seaming operation.

The upper surface of the supporting plate 10 is provided with a recessed portion extending around the opening therethrough beneath the seaming head. The supporting plate is also provided with a slot 26 which may be milled or otherwise suitably formed and which is disposed at one side of the opening beneath the seaming head. This slot 26 is illustrated as being arcuate and concentric with the center of the opening beneath the seaming head. An annular ring-shaped plate 27 is disposed within the recessed portion in the upper surface of the supporting plate 10 and extends around the opening beneath the seaming head. The seat 15 for the can ends is formed around this plate 27. The under surface of the annular plate 27 is provided with a plurality of radially directed slots 28 which form steam openings and which extend toward the opening beneath the seaming head. The outer edges of the slots 28 are in communication with the slot 26 so that steam passing into the slot 26 will be directed inwardly across the opening beneath the seaming head.

An opening 29 is drilled through the supporting plate 10 and is in communication with the arcuate slot 26. A steam supply pipe 30 is connected to the opening 29 by a suitable coupling 31, and passage of steam through the pipe 30 is controlled by a suitable form of valve mechanism (not shown) within the valve housing 32. In order to control passage of steam from any suitable high pressure steam source, the valve mechanism within the valve housing 32 is operated by movement of a reciprocating plunger 33 which is normally urged outwardly by spring means so as to normally close the valve mechanism and shut off communication between the steam supply and the arcuate slot 26.

The plunger 33 is actuated by a lever 34 for opening the valve mechanism and admitting steam to the slot 26 and the steam openings 28. The lever 34 is pivoted, as at 35, to a bracket 36 and is provided with a bearing surface 34a which is adapted to contact with the free end of the plunger 33. The lever 34 is provided with a stop shoulder 34b which cooperates with a part of the bracket 36 to limit outward movement of the lever away from the plunger 33.

An arm 37 is secured to the shaft 17 and to the sleeve 17a by bolts 38 or the like, and this arm is disposed beneath the supporting plate 10. The arm 37 extends radially from the shaft 17 toward the free end of the lever 34 which is provided with a roller 39. The free end of the arm 37 is provided with a cam surface 40 which is adapted to cooperate with the roller 39 on the lever 34 in a manner to be hereinafter fully pointed out.

As the arm 16 engages the can end at the bottom of the stack beneath the opening 13, this can end is moved along the trackway 14 and is ultimately positioned on the seat 15 around the opening beneath the seaming head. The end 18 of the arm 16 can then pass by the seated can end and substantially at this point, the cam surface 40 on the arm 37 comes into engagement with the roller 39 on the free end of the lever 34. Further movement of the cam surface 40 with the

arm 37, will tend to rock the lever 34 in a clockwise direction (as shown in Fig. 1) so as to force the plunger 33 inwardly of the valve housing by engagement between the surface 34a and the free end of the plunger. This inward movement of the plunger 33 will effect opening of the valve mechanism so as to admit high pressure steam through the pipe 30 into the slot 26. The steam thus admitted to the slot 26 will gain access to the steam openings 28 which are disposed at one side of the opening beneath the seaming head and which form a steam distributor so that the steam will issue in jets across the space between the seated can end and the can body when substantially in the position shown in Fig. 2.

The cam surface 40 on the arm 37 is constructed relative to the lever 34 and positioned on the shaft 17 in such a manner that the steam is admitted through the valve after the can end 15 has been seated within the opening beneath the seaming head. Similarly, the construction of these parts and the timing thereof is such that the steam will issue from the parallel steam openings 28 during movement of the can body toward the seated can end preparatory to the seaming operation. Thus, the steam which issues from the substantially parallel jets across the space between the can end and the can body, passes substantially as a blanket in one direction downwardly and across the head space of the filled can so as to effectively drive out all of the air present. As the can body approaches the seated can end, the cam surface 40 will pass the roller 39 on the lever 34 so as to permit the lever 34 to move in a counter-clockwise direction, thus closing the valve mechanism and shutting off the steam supply. Continued upward movement of the can body is effected in known manner so as to bring the can body and the can end into position for the seaming operation at the seaming head. The use of high pressure steam has been found to be advantageous in that it more completely sweeps out the air from the head space of the filled can by passing across the same at a relatively high velocity, and furthermore, in that it heats up the head space and the top of the can body so as to produce a higher vacuum when the steam condenses inside of the closed can.

While one form of the invention has been shown for the purpose of illustration, it is to be clearly understood that various changes in the details of construction and arrangement of the parts may be made without departing from the spirit of the invention as set forth in the appended claims.

I claim:

1. In a can closing machine in which a can end and a filled can are adapted to be moved relative to one another at the seaming station for properly positioning the same preparatory to the seaming operation, the combination of a seat for the can end at the seaming station, feeding means for directing a can end to said seat, a steam supply conduit, means providing passages for directing steam from said conduit below said seat across the head space of the filled can whereby to eliminate air therefrom, and means movable with said feeding means for controlling the passage of steam and being timed so as to direct steam across the head space of the filled can between the can and the can end during relative movement therebetween preparatory to the seaming operation.
2. In a can closing machine in which a can end and a filled can are adapted to be moved

relative to one another at the seaming station for properly positioning the same preparatory to the seaming operation, the combination of a seat for the can end at the seaming station, a feeding arm for directing a can end to said seat, a steam supply conduit, means providing passages disposed below said seat for directing steam from said conduit across the head space of the filled can whereby to eliminate air therefrom, means for controlling the passage of steam through said conduit, and cam means movable with said feeding arm for actuating said steam control means and timed so as to direct the steam across the head space of the filled can between the can and the can end during relative movement therebetween preparatory to the seaming operation.

3. In a can closing machine in which a can end and a filled can are adapted to be moved relative to one another at the seaming station for properly positioning the same preparatory to the seaming operation, the combination of a supporting plate having an opening therethrough at the seaming station, said supporting plate having a recessed portion extending around said opening and having a slot disposed at one side of said opening and upwardly communicating with the recessed portion, a ring member disposed in said recessed portion around said opening and having a seat for the can end, said ring member having a plurality of substantially parallel grooves in the undersurface thereof extending from said slot inwardly and communicating with said opening and forming with the adjacent surface of said plate a plurality of substantially parallel passages for directing steam as a blanket in one direction across the head space of the filled can whereby to eliminate air therefrom, and means for controlling the passage of steam through and passages and said controlling means being timed so as to permit the steam to be directed across the head space of the filled can between the can and the can end during relative movement therebetween preparatory to the seaming operation.

4. In a can closing machine in which a can end and a filled can are adapted to be moved relative to one another at the seaming station for properly positioning the same preparatory to the seaming operation, the combination of a seat for the can end at the seaming station, feeding means for directing a can end to said seat, a steam supply conduit, means providing passages for directing steam from said conduit below said seat across the head space of the filled can whereby to eliminate air therefrom, valve means in said conduit for controlling the passage of steam therethrough, a lever for actuating said valve means, and cam means movable with said feeding means for actuating said lever and timed so as to direct steam across the head space of the filled can between the can and the can end during relative movement therebetween preparatory to the seaming operation.

5. In a can closing machine in which a can end and a filled can are adapted to be moved relative to one another at the seaming station

for properly positioning the same preparatory to the seaming operation, the combination of a seat for the can end at the seaming station, a rotatable shaft, a feeding arm rotatable with said shaft for directing a can end to said seat, a steam supply conduit, means providing passages for directing steam from said conduit across the head space of the filled can whereby to eliminate air therefrom, valve means for controlling the passage of steam through said conduit and including a pivoted lever, and a cam arm rotatable in unison with said shaft and said feeding arm for actuating said lever and timed so as to permit the steam to be directed across the head space of the filled can between the can and the can end during relative movement therebetween preparatory to the seaming operation.

6. In a can closing machine in which a can end and a filled can are adapted to be moved relative to one another at the seaming station for properly positioning the same preparatory to the seaming operation, the combination of a supporting plate having an opening therethrough at the seaming station and said supporting plate having a recessed portion on the upper face thereof and extending around said opening, said supporting plate also having an arcuate slot disposed at one side of said opening and communicating with said recessed portion, a ring member located in said recessed portion around said opening and having a seat for the can end, the bottom edge of said ring member and the adjacent edge of said supporting plate being shaped to provide a plurality of substantially parallel passages extending from said arcuate slot to said opening, and conduit means for directing steam to said arcuate slot and through said passages whereby the steam will pass in one direction across the head space of the filled can in order to effect a blanket sweeping of air therefrom.

7. In a can closing machine in which a can end closure and an open topped filled can are adapted to be moved relative to one another in a vertical direction at the seaming station for properly positioning the same preparatory to the seaming operation, the combination of a supporting plate having an opening therethrough at the seaming station and a seat for a can end closure around said opening, said opening being shaped and dimensioned to permit movement upwardly therethrough of one can only during a can closing operation, said plate having a steam supply chamber at one side only of said opening and a plurality of substantially parallel steam discharge ports leading from said chamber to the opening for directing a stream of steam between the can end closure and the open can top and in one direction only across the head space of the filled can, said stream of steam being of a width substantially equal to the diameter of the can so as to provide a blanket of steam extending across the whole width of the open top of the can for sweeping the air from the head space of said can and filling the head space with steam.
